DESIGN FOR A CAN TOP

John Coyle and William F. Punte, Baltimore, Md.,
assignors to Continental Can Company, Inc.,
New York, N. Y., a corporation of New York

Application March 21, 1945, Serial No. 118,614

Term of patent 14 years

(Cl. D58—26)

To all whom it may concern:

Be it known that we, John Coyle and William F. Punte, citizens of the United States, and each a resident of Baltimore, in the State of Maryland, have invented a new, original, and ornamental Design for a Can Top, of which the following is a specification, reference being had to the accompanying drawing, forming a part thereof.

In the drawing:

Fig. 1 is a side elevational view of a can top showing our new design;

Fig. 2 is an end elevational view;

Fig. 3 is also an elevational view showing the end opposite that illustrated in Fig. 2; and

Fig. 4 is a top plan view thereof.

We claim:

The ornamental design for a can top, substantially as shown.

JOHN COYLE.
WILLIAM F. PUNTE.
